(57) **CLAIM**

The ornamental design for knitting needle, as shown and
described.

DESCRIPTION

FIG. 1 is a side view of a knitting needle;

FIG. 2 is a front view thereof, the opposite view being identical
to the front view;

FIG. 3 is a top view thereof; and,

FIG. 4 is a bottom view thereof.

The middle portion is broken away in FIGS. 1 and 2 to
indicate that a specific length of knitting needle forms no part
of the claimed design.
